UNITED STATES PATENT OFFICE.

JOSEPH P. DION AND JOHN P. KELLY, OF BIDDEFORD; SAID DION ASSIGNOR
TO GEORGE MOORE, OF BERWICK, MAINE.

HEEL-BURNISHING MACHINE.

SPECIFICATION forming part of Letters Patent No. 341,798, dated May 11, 1886.

Application filed April 6, 1885. Serial No. 161,267. (No model.)

To all whom it may concern:

Be it known that we, JOSEPH P. DION and JOHN P. KELLY, of Biddeford, in the county of York and State of Maine, have invented 5 certain new and useful Improvements in Devices for Finishing Heels of Boots and Shoes; and we do hereby declare that the following is a full, clear, and exact description of the invention, which will enable others skilled in 10 the art to which it appertains to make and use the same, reference being had to the accompanying drawings, and to letters of reference marked thereon, which form a part of this specification.

15 Figure 1 is a top plan view of our machine. Fig. 2 is a side elevation of the curved arm with the burnisher and its arm. Fig. 3 is a side elevation of the curved arm, with the burnisher and the plate that holds it and its 20 supporting-arm in position removed. Fig. 4 is a view in perspective of the burnisher and its arm or support. Fig. 5 is a side view of the jacking device, with a portion of the last in section. Fig. 6 is a vertical central section 25 through the center of the operating-shaft, disk, and stud. Fig. 7 is a detail view of the manner of uniting the two parts of the split expanding-pin.

Same letters show like parts.

30 Our invention relates to machines for burnishing the heels of boots and shoes.

It consists in various arrangements of devices for finishing the different portions of the heel, and it contains also a set of devices for 35 jacking or holding the shoe while the operation is being performed.

A is the base of the machine. b b' are two curved arms or supports rising from the base and carrying the shaft c, which has the pulley d, where power is applied. The shaft c carries the disk e at one end, set in a circular recess in the curved arm b'. A little out of the center of this disk is the stud f, projecting a short distance. This stud is intended to enter the hole g in the link h. The link h has also the hole i to receive a stud in the plate k'. This plate k' has a pivot which enters the hole m in the arm b'. It is there held by the screw-bolt n and the washer o. The screw-bolt n enters a screw-socket in the end of the pivot, and thus holds it by means of the washer o. We

are now enabled to see that when the shaft c is made to revolve a vibratory motion is imparted to the plate k'. The purpose of this will now be explained. This plate k' has a 55 channel, r, on its outer side, which is covered by the covering-plate s. Into this channel is fitted the arm t with a shoulder, u, on it, a part, v, and a spiral spring, w. On the outer end of this arm t are set the burnishing devices, which, all taken together, we will designate by B. We will, as the description progresses, designate the parts by other letters. This entire device or set of devices, it will now be understood, has a rapid vibratory 60 motion on the arm t. The part x is to give a polish or burnish to the whole edge of the heel, and may be curved and shaped so as to fit heels of any desirable shape. It exhibits corrugations drawn diagonally across its surface. These are rounded in form, as seen in Fig. 4. The object of the corrugations is to give a polish in which the blacking is worked into the leather, which a plain surface would not do. The diagonal direction gives a better 70 friction on the heel. This part of the burnisher is used after the part y, which we will now describe. The part y is to give a smooth or finished edge to the top lift of the heel. This is difficult to do, and in many machines and in 75 hand-work the edge of this lift is often left ragged and irregular. With the use of a mere plain surface it would require much more time. The edge of the top lift is pressed with proper firmness into the angle z, and by the combined 80 action of the corrugated surface y and the smooth surface d', at right angles thereto, a smooth polished edge is given to the top lift. It will be seen that the part x, near the smooth portion d', has a somewhat more abrupt curve 85 than at other portions. The object of this is to prevent the smoothed and finished edge of the top lift from coming in contact with the burnisher at all after it has once been finished on the parts just above described—to wit, y 90 and z. The part x is where the operation is performed on the side of the heel after the top lift has been polished, as before specified. The edge d' is to give the marking or beading to the top of the heel, or the edge just where 95 it comes in contact with the upper. It is composed of the ridges 1 2 3. The ridge No. 1 is 100

to go over the edge of the lift or in between it and the upper. Ridge 2 is the one that makes the marking or beading on the edge of the lift. Ridge 3 is a gage to prevent ridge 2 from entering into the leather too deeply. Thus the usual figuring or beading is impressed on the heel at this point, and the edge of the lift made smooth.

The arm *t*, as has been shown, has the spiral spring, one end bearing against the shoulder *u*, and the other against the end of the channel *r*. This is to relieve the pressure on the heel of the boot or shoe if the operator should press too hard.

15 Rising from the base *A* is the standard *C*. Over this standard fits a head, *f'*, through which slides the horizontal stock *g'*. The stock *g'* carries the devices for jacking or holding the boot or shoe while the heel is being finished. 20 First, is the horizontal joint *i'*, admitting of the boot or shoe being so turned as to aid in presenting all parts of the heel to the burnishing device; second, is the jack or device for holding the boot directly. This is done by a split 25 expanding pin, *j'*, which enters the hole in the top of the last. The pin is inserted when the two parts are closed. When once inserted, the parts are expanded, and thus the pin is held firmly and securely in the hole in the last. The 30 boot or shoe is on the last. It is thus presented to the burnishing devices for finishing the heel.

The split expanding pin *j'* is operated in this manner. The two parts *l m* of the split expanding pin are connected with two curved arms, *n' o'*. A straight part, *p'*, of these two arms passes through a head, *q'*. The straight part *p'* is united in the manner shown in Fig. 5, where one-half of the straight part has two jaws and the other a tongue to fit between them. 40 This is illustrated in the detail, Fig. 7. A pin passes through the head *q'* and the tongue and jaws, and thus furnishes a pivot for the movement of the two parts of the split expanding pin.

45 *s'* is a bifurcated lever pivoted to the curved arm *n'*.

t' is a lever pivoted at *v'* in the bifurcations of the lever *s'*. The arm *o'* also passes in through 50 the bifurcations of the lever *s'*.

55 *u'* is a curved rack on the curved arm *n'*, into the teeth of which fits the end of the lever *t'* like a pawl. A spring, *w'*, keeps the end of the lever *s'* pressed into the teeth of the rack *u'*, in order to hold the two levers at any desired point. The pivot *v'* also carries the two rollers *x'*, and these come in contact with the face of the curved arm *o'*, and by 60 pressing it upwardly open the two parts of the split expanding pin. (See Fig. 5.) By moving the bifurcated lever *s'* forward the curved arm *o'* is brought up nearer to the arm *n'*, and thus the two parts of the split expanding pin are forced apart. Thus when the pin 65 is entered into the hole in a last, which last is in a shoe, it (the pin) can be made to fit

very tightly and hold itself very firmly in said hole.

The split expanding pin with its accompanying devices is capable of a complete rotation in a vertical plane. This is accomplished by the pin *a'*, socket *b'*, groove *d'*, and screw *c'*. The pin *a'* enters the socket *b'*, and the screw *c'* enters the groove *d'*. Thus the entire portions of the device, including the friction-joint, the split expanding pin, the curved arms, and the two levers, can revolve as described. This motion is produced in order to give that complete revolution to the shoe which is necessary in order to present all parts of the heel all around to the action of the burnishing devices before described. Some lasts have the holes made in them at an inclination or angle. If there were no way to correct the effect of this, the shoe could not be properly presented to the burnisher. The shoe must always be so presented, straight or level, and without any inclination. To insure this, a friction-joint is made at *y'*, which admits of an inclination being given to the split expanding pin to correct the inclination there may be in the hole of the last. The stock *g'* is made to slide in the head *f'*. This movement may become desirable and necessary from the size of the shoes, which may require the stock to be pushed back or forward somewhat while the heel is being operated upon.

We do not claim any of the combinations patented to Joseph P. Dion in Patent No. 290,554, December 18, 1883.

What we claim as our invention, and desire to secure by Letters Patent of the United States, is—

1. The combination, with the shaft *e*, of the disk *e*, link *h*, plate *k'*, arm *p*, and the burnishing tool, as herein set forth.

2. The burnisher *B*, having the parts *x*, *d''*, *y*, and *d'*, carried by the arm *t*, in combination with suitable operating mechanism, substantially as described.

3. In a burnishing machine, the plate *k'*, having the channel *r* for the arm *t*, and operated by means of the link *h*, the stud, the disk *e*, the pivot, and a suitable burnishing tool, as set forth.

4. In a burnishing machine, the last-supporting mechanism consisting of a standard carrying the head *f'*, the stock *g'*, inserted through the head, in combination with a split expanding pin and the mechanism for operating the same, as herein set forth.

5. In a burnishing machine, the last-supporting mechanism consisting of a standard carrying the head *f'*, and the stock *g'*, inserted through the head and having the hinged or pivoted part *i'*, in combination with a split expanding pin and mechanism for operating the same, as herein described.

6. In a burnishing machine, the last-supporting mechanism consisting of a standard carrying the head *f'*, the stock *g'*, inserted through the head, the joint *y'*, pin *a'*, socket

*b*³, and screw *c*³, in combination with a split expanding-pin and mechanism for operating the same, as herein set forth.

7. In a burnishing-machine, a last-supporting mechanism consisting of a suitable standard carrying a split expanding-pin, *j*, and suitable mechanism for operating the same, as herein described.

8. In a burnishing-machine, the last-supporting mechanism, consisting of a standard carrying the head *f'*, the stock *g'*, inserted

through the same, and the socket *b*³, in combination with a split expanding-pin and mechanism for operating the same, as herein described.

In testimony that we claim the foregoing as our own we affix our signatures in presence of two witnesses.

JOSEPH P. DION.
JOHN P. KELLY.
